(57) **CLAIM**

The ornamental design for an “air vent cover,” as shown and described.

DESCRIPTION

FIG. 1 is a perspective view of a first embodiment of an air vent cover showing our new design;

FIG. 2 is a right side view of the cover of FIG. 1, the left side view being a mirror image thereof;

FIG. 3 is a top view thereof, the bottom view being a mirror image;

FIG. 4 is a front view thereof;

FIG. 5 is a rear view thereof;

FIG. 6 is a perspective view of a second embodiment of an air vent cover showing our new design;

FIG. 7 is a right side view of the cover of FIG. 6, the left side view being a mirror image thereof;

FIG. 8 is a top view thereof, the bottom view being a mirror image;

FIG. 9 is a front view thereof;

FIG. 10 is a rear view thereof;

FIG. 11 is a perspective view of a third embodiment of an air vent cover showing our new design;

FIG. 12 is a right side view of the cover of FIG. 11, the left side view being a mirror image thereof;

FIG. 13 is a top view thereof, the bottom view being a mirror image;

FIG. 14 is a front view thereof; and,

FIG. 15 is a rear view thereof.

The brackets drawn in broken lines show use and environment, and form no part of the claimed design.
